Edw. J. Delany, of Philadelphia, Pa.
Assignor to
Henry E. Marsh and Jas. Johnson, of Lawrenceville, Pa.
Letters Patent No. 1026, dated July 13, 1858.

The schedule referred to in these Letters Patent and making part of the same.

To all whom it may concern:

Be it known that I, Edward J. Delany, of the City of Philadelphia and State of Pennsylvania, have invented or produced a new and original design for the plates of a Cooking Stove termed the "Governor Penn" and I do hereby declare the following to be a full and exact description of the same, reference being had to the accompanying drawing, which forms a part of this specification and in which.

Fig. 1. represents the side plate of the Stove with the edges of the top and bottom plates.

Fig. 2. a view of the front of the Stove.

Fig. 3. a view of the back.

Fig. 4. a plan of the top plate of the stove.

The side plate (Fig. 1.) has a plain molding (a) at the top a plain molding (B) of different pattern at the bottom and a short molding (C) where the hearth is situated. This plate has also the usual oven doors (A) and (B) both edged with plain moldings and both having filiated ornaments in alto-relievo. Above the oven door (B) is a panel (E) edged with a plain molding and having a foliated ornament similar in character to that of the oven door (A). On the plate and above the last named door is a foliated scroll (D) with the name of the stove in raised letters.

The front of the stove consists of an upper plate (E) and a lower plate (F) both having moldings similar to those of the side plate.

The upper plate (E) has two fire-place doors (G) & (G') both edged with plain moldings and both having foliated ornaments. Above these doors are a series of openings (D) with ornamental sprigs between them.

The lower front plate (F) has two foliated scroll ornaments (E), (E').

The back plate (Fig. 3) has also upper and lower moldings similar to those of the side plate and a central foliated ornament forming three panels.

I claim and desire secure by Letters Patent, The several plates with their ornamental figures and forms represented in and by the accompanying drawings and forming together an ornamental design for a Cooking Stove.

In testimony whereof, I have signed my name to this Specification before two subscribing witnesses.

Witnessed,

Henry Dawson,

Henry Odiorne,

W. J. Delany.
